UNITED STATES PATENT OFFICE.

MARSHALL I. WILLIAMSON, OF BALTIMORE, MARYLAND.

VIBRATORY-DIAPHRAGM CONTROLLER.

Application filed April 28, 1925. Serial No. 26,323.

This invention relates to improvements in such instruments as are equipped with vibratory diaphragms for the production or reproduction of etherial or other vibrations resulting in sensible effects such as may be perceived by the ear or other sense either directly or indirectly.

One principal object of the invention is to provide improved means for adjustably controlling the vibrations, irrespective of their cause, of the diaphragm in such instruments and to render the sensitivity of such diaphragms minutely adjustable over a wide range of impulse frequencies thereby to enable nice and easy variation and regulation of the effects resulting from their vibratory activities.

A second object of the invention is to provide an adjustable controlling and regulating means of the character set forth, which is entirely independent of the elements or forces which cause vibrations of such diaphragms.

A third object of the invention is to provide an improved adjustable, controlling and regulating means of the character set forth which is extremely simple in construction and operation and entirely practical from the standpoints of commercial manufacture and sale.

A fourth important object of the invention is to provide an improved device for controlling the amplitude of vibration of the diaphragm such as is used in the receiver or reproducer of a phonograph, in a telephone, in a radio loud speaker and in other instruments wherein a diaphragm forms the vibratory element.

A fifth important object of the invention is to provide an improved diaphragm mounting for instruments employing a diaphragm as a vibratory element, the mounting being so arranged as to permit adjustment of the amplitude of vibration of the diaphragm through a wide range under equal impulses received by said diaphragm.

With the above and other objects in view as will be hereinafter apparent, the invention consists in general of certain novel details of construction and combinations of parts hereinafter fully described, illustrated in the accompanying drawings and specifically claimed.

In the accompanying drawings like char-

acters of reference indicate like parts in the several views, and:

Figure 1 is a vertical median section through an instrument embodying the principles of this invention, the instrument being shown of the type preferably adapted to be employed for radio-signal or radio-telephone reproduction and being of the type commonly called a loud-speaker.

Figure 2 is a top plan view of the device shown in Figure 1 with the base omitted.

Figure 3 is a section on the line 3—3 of Figure 1.

Figure 4 is a vertical median section of a certain split collar used herewith.

Figure 5 is a similar view of one of a pair of certain resilient pads used herewith.

Figure 6 is a side elevation of the invention as shown in Figure 1, with the outer collar omitted.

Figure 7 is an enlarged detail section through the periphery of the invention.

Figure 8 is a plan view of a certain rubber covered spiral spring adapted for use as an alternative of the elastic pad shown in Figure 5.

Figure 9 is an edge view of the spring shown in Figure 8.

Figure 10 is a side elevation, partly in section, of the invention as applied to a phonograph reproducer.

Figure 11 is a view similar to Figure 10 showing the invention applied to a telephone receiver.

In the invention as disclosed in Figure 1 there is provided a shallow cylindrical cup having a side wall 10 which is internally threaded at its bottom end to receive the bottom 11 of the cup, this bottom having a lever 12 secured thereto, so that it may be rotated and caused to rise or lower with respect to the side wall 10. On this bottom is mounted a small electro-magnet 13, of the telephone or radiophone receiver type, and this magnet is centrally seated on the bottom. At its upper edge the side wall 10 is provided with several turns of internal or female threading. At 14 is a six flanged washer-like spider, the diameter of which, at the base of the flanges, is slightly less than the inside diameter of the member 10, while the diameter of the flanges or projections 15 is slightly greater than the outer diameter of said member 10. The outer faces of

these flanges 15 are right hand threaded continuously from one to another, the gaps between the flanges thus causing the member to constitute an interrupted screw. The inside diameter of this spider is just great enough to permit its free passage over and around the poles of the electro-magnet 13, these poles extending somewhat above the cup formed by the members 10 and 11. At 16 is a short cylinder having internal and external diameters corresponding to those of the cylindrical portion 10 of the cup. The lower edge of this cylinder is deeply crenellated by six slots of slightly greater width than the flanges or projections 15 and these slots are approximately twice as deep as the thickness of said flanges. Moreover, their spacing corresponds with the spacing of the flanges 15, so that said flanges will fit neatly in said slots. This member 16 is threaded at the top and bottom, the threads being, of course interrupted at the slots and by means of these threads the member is threaded into the upper edge of the member 10. Thus the flanges 15 project through the slots 16 and the member 14 is thereby held in position while being capable of a limited vertical movement. On the threaded upper portion of this cylinder is screwed an internally threaded annular collar 17, the inside diameter and threads of which are such as to enable it to be connected for half its depth on the threads at the top of the cylinder 16. At 18 is a second short slotted cylinder identical with the cylinder 16 but inverted so as to be threaded into the upper half of the thread in the collar 17, and at 19 is a spider similar in all respects to the spider 14 except that the threads on the flanges 20 of this spider are left hand threads. On the upper end of the second slotted cylinder 18 is screwed a cup shaped member 21 provided with a hollow spindle or tube 22 for engagement by a horn. Thus the upper spider is held between the upper hollow cylinder and the upper cup shaped member 21. Between these two spiders are mounted a pair of resilient pads 22' having confronting concave sides and between these two pads is a thin vibratory diaphragm 23 slightly greater in diameter than the inner diameter of the cylinders 16 and 18 which thus securely grip the diaphragm at its periphery. Surrounding these parts is an annular collar consisting of an upper member 24 threaded internally to engage the threads on the member 19 and a lower member 25 threaded internally to engage the threads on the member 14. Thus, the two parts of the collar are threaded to engage the right and left hand threading on the flanges of the upper and lower spiders and, when these two parts are locked against relative movement, as by screw 26, they may be rotated simultaneously to move the two spiders toward each

other, when rotation is in one direction, and away from each other when the rotation is in the opposite direction. In this manner the two resilient pads may be compressed and the diameter of the diaphragm 23 may be increased or diminished at will. In place of such pads 22' spiraform rubber covered springs 27 may be employed and the parts may be locked together, when desired, by screws 28. Suitable graduations 29 may be used on the split collar and a pointer 30 on the member 21 may also be used to indicate the adjustment obtained.

It will be obvious that in place of the electric magnet 13 a needle arm may be used as shown in Fig. 10 and that instead of the tube 22 an ear piece may be employed as in Fig. 11.

With the foregoing arrangement it will be seen that rotating the split collar in one direction and decreasing the diameter of the diaphragm will decrease the amplitude of vibration of such diaphragm while, rotation of the split collar in the opposite direction will increase the diameter and permit increase of the amplitude of vibrations of the same actuating conditions.

It is a recognized fact that all vibratory diaphragms have what are known as their natural period of vibration, which are the normal or simplest of their multifarious modes of vibratory activity. That different diaphragms, diaphragms of different materials, of different sizes, shapes and thicknesses have different natural periods of vibration and require different degrees or stages of vibratory impulse to actuate them. Moreover, two diaphragms of the same material and of the same thickness and shape but of different size, will have different natural vibratory periods, and will consequently produce different vibratory effects throughout their entire ranges of activity. From this, it will be seen that varying the size of a given diaphragm, without changing its thickness or general shape, will vary both its mass and its stiffness or tension. The present invention provides means for varying the effective mass of the diaphragm and for varying the stiffness or tension of said effective mass or area and by so doing, the diaphragm can be tuned at will, and without shifting the diaphragm from the position to which it has been adjusted.

It is obvious that the minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. A device of the character described

comprising a circular vibratory diaphragm, cylinders applied to the opposite surfaces of the diaphragm and having parallel inner surfaces which lie upon the peripheral portions 5 of the diaphragm and which extend beyond the peripheral edge of the diaphragm, a collar adjustably retaining the cylinders, elastic washers arranged upon the opposite sides of the diaphragm and bearing 10 against the inner edges of the cylinders, rigid washers engaging the elastic members on the side remote from the diaphragm and a means mounted upon the collar for shifting the washers laterally with relation to 15 the diaphragm.

2. In a device of the kind described, a vibratory diaphragm, elastic washers arranged on opposite sides of said diaphragm and each having a shallow concavity in the side 20 next to the diaphragm, rigid washers engaging the elastic members on the side remote from the diaphragm, said washers having right and left hand threads on their peripheries respectively, and a collar engaging 25 said washers and having internal right and left hand threads at its ends.

3. In a device of the kind described, a vibratory diaphragm, elastic washers arranged on opposite sides of said diaphragm 30 and each having a shallow concavity in the side next to the diaphragm, rigid washers engaging the elastic members on the side remote from the diaphragm, said washers having right and left hand threads on their 35 peripheries respectively, a collar engaging said washers and having internal right and left hand threads at its ends and a cage supporting said washers against rotation.

4. In a device of the kind described, a vibratory diaphragm, elastic washers arranged on opposite sides of said diaphragm and each having a shallow concavity in the side 40 next to the diaphragm, rigid washers engaging the elastic members on the side remote from the diaphragm, a cage surrounding the washers and diaphragm and provided with spaced peripheral slots, arms on said washers projecting through said slots and interrupted right hand threads on the outer edges 45 of the arms of one washer and interrupted left hand threads on the outer edges of the 50

arms of the other washer, and a collar fitting over said arms and internally threaded to engage the same.

5. In a device having a vibratory diaphragm, adjustable members parallelly arranged on opposite sides of the diaphragm and having projecting flanges at their peripheries, a surrounding frame adapted to engage said flanges thereby to support the 55 said members against rotation or lateral movement while permitting a limited movement thereof directly toward and from each other, and means for arbitrarily effecting such limited movement of the said members 60 within the aforesaid frame.

6. In a device having a vibratory diaphragm, adjustable members arranged parallelly on opposite sides of the diaphragm and a surrounding frame or housing within 70 which said members are peripherally held, said members having interlocking elements with the housing, lateral movement within the housing, and means for engaging the protruding peripheral flanges of said members 75 externally of the housing whereby simultaneously to move the said members directly toward and from each other therewithin.

7. In a device having a vibratory diaphragm, a supporting housing therefor the 80 walls of said housing being perforated by peripherally spaced slots adjustable coacting members having correspondingly spaced protruding flanges on their peripheries, said members being arranged diametrically with 85 in the housing and supported against rotation while permitting a limited movement thereof directly toward and from each other, and a single or unified external means for arbitrarily effecting such limited movement 90 of the said members within the housing.

8. In a device comprising a supporting housing for a vibratory diaphragm, an external collar, partially protruding adjustable coacting members supported by the collar within the housing, and means within the 95 said collar for variably changing the positions of said coacting members within the housing.

In testimony whereof I affix my signature.

MARSHALL I. WILLIAMSON.
